ELECTRIC LAMP

Emil Teleki, 125 E. 15th St., New York, N.Y. 10003

Filed Dec. 27, 1967, Ser. No. 9,936

Term of patent 14 years

(Cl. D48—20)

FIG. 2 is a top plan view,

FIG. 3 is a side elevational view thereof,

FIG. 4 is a front elevational view thereof, and

FIG. 5 is a rear elevational view thereof.

The light bulb shown in broken lines in FIG. 1 and FIGS. 3—5 is for illustrative purposes only.

I claim:

The ornamental design for an electric lamp, substantially as shown and described.
